TAPERING MECHANISM

George M. Pelton, deceased, late of Milwaukee, Wis., by Herbert W. Knox, administrator, Milwaukee, Wis., assignor to The Filer & Stowell Company, Milwaukee, Wis., a corporation

Original application August 11, 1930, Serial No. 474,583. Divided and this application July 20, 1931, Serial No. 552,003

8 Claims. (Cl. 121—45)

- This invention is directed to an improvement in tapering mechanisms for saw mill machinery, wherein the taper movement of the knee may be selectively controlled at will.
- 5 The primary object of the invention is the provision of a tapering mechanism through which the knee may be moved relative to the head block for a unit taper distance or for any one of several multiples of such unit taper distance through the provision of power mechanism of simple and compact form.
- 10 A further object of the invention is the utilization in such taper mechanism of means for cushioning the movement of the knee under initial log impact whereby to absorb the jar of such impact to avoid undue strain and possible breakage of the parts.

- The invention is illustrated in the accompanying drawings, wherein:
- 20 Figure 1 is a side elevation of the tapering mechanism in applied position.
- Figure 2 is a longitudinal section through the tapering mechanism.
- 25 Figure 3 is a view similar to Figure 2, showing the position of the parts following the operation of the pressure piston.

- Figure 4 is a view similar to Figure 2, showing the position of the parts following the initial operation of the pressure piston and the subsequent operation of the limiting piston.

- 30 Figure 5 is a view similar to Figure 2, showing the position of the parts following the operation of the operating piston.

- The present invention contemplates the use of 35 tapering mechanism wherein a knee, irrespective of the position of the dogs, may be moved transversely of the carriage independently of the set works in order that such knee may accommodate itself to the irregular formation of the log in order that a proper sawing operation may be had. This tapering means, as illustrated in the drawings, is designed to provide tapering movements of the knee in multiples of a predetermined minimum taper, and is also constructed to provide a cushion for the movement of the knee resulting from the impact of the log rolled against the knee.

- The tapering mechanism comprises a cylinder 70 of appropriate interior volume, bolted to 50 the head block through spaced walls 71, between which the knee 1 slidably extends and to which the knee is connected by transverse bolts 72 between the walls passing through the elongated slots 73 in the knee. A hollow piston 74 is mounted within and adapted for sliding coop-

eration with the forward portion of the cylinder 70, the rearward movement of this piston being limited by a shoulder 75 on the interior of the cylinder. The piston 74 is formed with a transverse wall 76 and with a rearwardly extending skirt 77 terminating in a piston disk 78 hereinafter termed the operating piston which, through the medium of appropriate piston rings, has a sealing sliding fit with the interior of the cylinder 70.

5 The wall 76 of piston 74 has a rearward, sleeve-like extension 79 in which is slidably fitted a hollow, sleeve-like extension 80 projecting rearwardly from a power piston 81 which has a sealing sliding fit with the piston 74 and which is limited in its movement outwardly of said piston, as at 82. The piston 81 is connected by a link 83 with the knee 1.

Arranged in the cylinder 70 rearwardly beyond the piston disk 78 is a piston disk 84 hereinafter termed the limiting piston arranged for sliding sealing cooperation with the cylinder 70 and carrying a piston rod 85 which projects forwardly of the piston disk 84 and extends loosely through an opening in the piston disk 78 and terminates in a head 86 having a diameter greater than that of the interior of the sleeve-like extension 79. The opening in the piston disk 78 through which the rod 85 extends is surrounded by a sleeve 87, the interior diameter of which is sufficient to receive the head 86. The piston rod 85 extends in the opposite direction from the piston disk 84 relative to the head 86 and through the end of the cylinder, as at 88, and terminates in an enlargement 89.

35 Between the piston disk 84 and the proximate end of the cylinder, that is, the rear end, is arranged a third piston disk 90 hereinafter termed the pressure piston having a sliding sealing fit with the cylinder 70 and centrally of which piston disk 90 there is secured a sleeve 91 which snugly and slidably fits the piston rod extension 88 and terminates in a head 92. The end wall of the piston has a guiding extension for the sleeve 91, as at 93, which extension is formed with a channel 94 of an interior diameter sufficient to receive the head 92 and of a predetermined depth to limit thereby the movement of the head toward the opposite end of the cylinder.

40 The cylinder 70 is formed immediately adjacent the shoulder 75 with an inlet 95 to constantly admit air under pressure. The air finds its way longitudinally of the cylinder 70, about the skirt 77, and enters the interior of the skirt through openings 96 formed in the skirt adj-

cent the piston disk 78. The transverse wall 76 of the hollow piston 74 is also formed with openings 97 so that air under pressure fills the space within the skirt 71 and between the wall 76 and 5 the piston 81. Thus, by pressure on the piston disk 78, all parts are held at their rearward limit, that is, in non-taper position. At the same time, the piston 81 is held in its advanced position by the air under pressure and such provides 10 a constant cushion to absorb the movement of the knee under impact of a log.

The end wall of the cylinder is formed with a port 98 which opens to the interior of the cylinder beneath the piston disk 90 so that in 15 the operation of this disk the disks 84 and 78 are correspondingly operated. The head 92 of the sleeve 91 is formed with a port 99 for the admission of air under pressure, which air passes longitudinally of the sleeve 91 about the piston 20 rod 88 and engages beneath the piston disk 84 to thereby move said disk longitudinally of the cylinder and with it the piston disk 78. The head or enlargement 89 of the portion 88 of the piston rod is formed with an inlet port 100 for air 25 under pressure which communicates with a central, longitudinally extending channel 101 formed in the piston rod 88, which channel communicates with a diagonal passage 102 formed in the piston disk 84 and opening beneath the piston 30 disk 78 so that under pressure through the port 100 the piston disk 78 and parts connected thereby are alone moved.

Assuming that the limit movement permitted the head 92 is the unit of movement for taper 35 purposes, say $1\frac{1}{2}$ ", then the limit of movement permitted the enlarged terminal 89 of the piston rod 88 before such enlargement contacts with the head 92 will be twice this unit or 3". The movement permitted the piston disk 78 by the head 86 is also 3". Pressure, therefore, is admitted through the port 98 to directly operate the piston disk 90, and the parts including the piston 81 connected to the knee will be moved until the head 92 is stopped by the extension 40 of the rear wall of the cylinder, that is, $1\frac{1}{2}$ ". If pressure is admitted through the port 99 to directly operate the piston disk 84, then the parts will be moved until the enlargement 89 of the piston rod 88 engages the head 92 of the 45 sleeve 91, that is, 3". If air is admitted simultaneously through the ports 98 and 99, the movement of the piston disk 90 through the $1\frac{1}{2}$ " permitted by the limit movement of the head 92 will thereupon space that head from the enlargement 89 of the piston rod 88 a distance of $4\frac{1}{2}$ " so that the pressure admitted through the port 99 will move the piston disk and the corresponding parts of the taper mechanism a distance of $4\frac{1}{2}$ ".

60 Therefore, under pressure admitted through the port 99, the piston disk 84 will engage piston 78 and move the hollow piston 74 and connected parts 3" for correspondingly moving the knee a like tapering distance. If pressure is admitted 65 through the port 100, the piston disk 78 is operated to the limit permitted by the head 86 and thus the corresponding parts of the mechanism are moved a distance of 3" for tapering movement of the knee to this extent.

70 If now pressure is correspondingly admitted through ports 99 and 100, the piston disk 84, moves the parts 3" and the piston disk 78 will correspondingly move the parts a further 3". Thus a taper of 6" for the knee is secured. If 75 pressure is simultaneously admitted through the

ports 98, 99 and 100, it is quite apparent that the piston disk 90 will move $1\frac{1}{2}$ ", permitting a movement of the piston disk 84 to $4\frac{1}{2}$ " or 3" farther than the movement of the piston disk 90, and the piston disk 78 will be moved a further 5 3" or $7\frac{1}{2}$ " complete movement of the parts connected with the knee and insuring a corresponding $7\frac{1}{2}$ " taper movement of the knee. Thus, by controlling the air pressure to the particular ports desired, the taper mechanism and 10 thereby the knee may be moved a distance of $1\frac{1}{2}$ " or any of the several multiples thereof up to $7\frac{1}{2}$ ".

Of course, the unit of movement arbitrarily indicated as $1\frac{1}{2}$ " may be obviously any unit, 15 and thus the knee may be selectively tapered to the particular unit or any of the several multiples thereof in a simple, expeditious manner. On release of the operating pressure, the constant pressure through the inlet 95 will return 20 all parts to normal or non-tapering position, as will be obvious.

This application is a division of application filed August 11, 1930, Serial #474,583, and issued as Patent No. 1,853,775 on April 12, 1932. 25

What is claimed is:

1. In a tapering mechanism a cylinder, a power piston in one end of said cylinder, three pistons arranged at the opposite end of the cylinder, the first of said pistons being normally in contact with the end of the cylinder, the second of said pistons overlying and normally in contact with the first piston, the third of said pistons overlying and normally in contact with the second piston, means carried by the first 35 piston to engage the cylinder in the operation of that piston and limit the movement of the piston, means carried by the second piston to engage the limiting means carried by the first piston in the movement of the second piston 40 to thereby limit the movement of the second piston, means carried by the second piston to limit the movement of the third piston, and means for selectively admitting fluid under pressure between the first piston and the end of the 45 cylinder, between the first and second pistons and between the second and third pistons, the movement of any one of said pistons being communicated to the power piston.

2. In a tapering mechanism a cylinder, a power 50 piston in one end of said cylinder, three pistons arranged at the opposite end of the cylinder, the first of said pistons being normally in contact with the end of the cylinder, the second of said pistons overlying and normally in contact with the first piston, the third of said pistons overlying and normally in contact with the second piston, means carried by the first piston to engage the cylinder in the operation of that piston and limit the movement of the piston, means carried by the second piston to engage the limiting means carried by the first piston in the movement of the second piston to thereby limit the movement of the second piston, means carried by the second piston to limit the movement of the third piston, means for selectively admitting fluid under pressure between the first piston and the end of the cylinder, between the first and second pistons and between the second and third pistons, the movement of any one of said pistons being communicated to the power piston, and means for admitting fluid under pressure between the third piston and the power piston. 70

3. In a tapering mechanism a cylinder closed 75

- at one end and open at the other, a power piston operative in the open end of the cylinder, a sleeve movable in the cylinder and slidably receiving and guiding said piston, three pistons arranged 5 in the cylinder beyond the end of the sleeve, the first piston being normally in contact with the closed end of the cylinder, the second piston being normally in contact with the first piston, the third piston being normally in contact with the 10 second piston and in engagement with the end of the sleeve, a piston rod extending from the second piston beyond the closed end of the cylinder and formed with a limiting abutment, said rod extending forwardly within the cylinder 15 through and beyond the third piston and serving as a limit for the movement of the third piston, a sleeve secured to the first piston encircling said piston rod and extending beyond the closed end of the cylinder, said piston sleeve terminating in an abutment to limit the movement of the 20 first piston and serve as a stop for the abutment of the second piston, a conduit for admitting air under pressure between the closed end of the cylinder and the first piston, a conduit in 25 the sleeve extension of the first piston to admit air under pressure between the first and second pistons, and a conduit extending longitudinally of the piston rod and opening between the second and third pistons to admit air under pressure 30 between the second and third pistons.
4. In a tapering mechanism, a cylinder, a power piston therein, a plurality of independent auxiliary pistons controlling the movement of the power piston, said auxiliary pistons including an 35 operating piston, a limiting piston and a pressure piston, means for admitting pressure to the cylinder for selectively operating said auxiliary pistons, a cylinder-engaging stop carried by the pressure piston to limit the operative movement 40 thereof, a stop carried by the limiting piston to engage the stop carried by the pressure piston to limit the operative movement of the limiting piston in accordance with the position of the stop of the pressure piston, and means carried by the 45 limiting piston to determine the limit movement of the operating piston.
5. In a tapering mechanism, a cylinder, a power piston therein, a plurality of independent auxiliary pistons controlling the movement of the power piston, said auxiliary pistons including an 50 operating piston, a limiting piston and a pressure piston, means for admitting pressure to the cylinder for selectively operating said auxiliary pistons, a cylinder-engaging stop carried by the pressure piston to limit the operative movement thereof, a stop carried by the limiting piston to engage the stop carried by the pressure piston to limit the operative movement of the limiting piston in accordance with the position of the stop of the 55 pressure piston, and means carried by the limiting piston to determine the limit movement of the operating piston.
6. In a tapering mechanism, a cylinder, a power piston therein, an operating piston movable in the cylinder for actuating the power piston, a limiting piston in the cylinder and arranged beyond the operating piston and normally in contact therewith, means carried by the limiting piston to limit the operative movement of the operating piston, a pressure piston arranged in the cylinder immediately beyond and normally in contact with the limiting piston, means carried by the pressure piston to limit the operative movement thereof, means carried by the limiting piston to cooperate with the limiting means of the pressure piston to limit the operative movement of the limiting piston, and means for admitting pressure for selectively operating the 60 pressure piston, limiting piston or operating piston.
7. A tapering mechanism including a pressure-operated means for selectively providing variable taper distances, said means including a cylinder 65 and a plurality of taper-controlling pistons movable in the cylinder, said pistons including an operating piston, a limiting piston and a pressure piston arranged in axial alignment, means for admitting pressure between the cylinder and the pressure piston to operate the latter, means for admitting pressure between the pressure piston and limiting piston to operate the latter, means for admitting pressure between the limiting piston and operating piston for operating the latter, a cylinder-engaging stop carried by the pressure piston to limit the operative movement thereof, a stop carried by the limiting piston to engage the stop of the pressure piston to limit the operative movement of the limiting piston, and a second stop carried by the limiting piston for limiting the operative movement of the operating piston.
8. A tapering mechanism including a pressure-operated means for selectively providing variable 70 taper distances, said means including a cylinder and a plurality of taper-controlling pistons movable in the cylinder, said pistons including an operating piston, a limiting piston and a pressure piston arranged in axial alignment, means for admitting pressure between the cylinder and the pressure piston to operate the latter, means for admitting pressure between the pressure piston and limiting piston to operate the latter, means for admitting pressure between the limiting piston and operating piston for operating the latter, a cylinder-engaging stop carried by the pressure piston to limit the operative movement thereof, a stop carried by the limiting piston to engage the stop of the pressure piston to limit the operative movement of the limiting piston, and a second stop carried by the limiting piston for limiting the operative movement of the operating piston, the limit of the operative movement of the limiting piston being dependent upon the position of the stop of the pressure piston and the limit of operative movement of the operating piston being determined by the piston of the second stop of the limiting piston.
